(51) LOC (11) Cl. 13-03

CLAIM

(52) U.S. Cl.

The ornamental design for an indoor cabinet with surface ornamentation, as shown and described.

USPC **D13/152**

DESCRIPTION

(58) **Field of Classification Search**

USPC D14/242, 240, 355, 357, 358, 125, D14/140–140.9, 155, 137, 139, 243, 239, D14/433, 314, 496, 188, 348, 351, 356; D13/152

CPC H04L 12/00; H03K 17/00; H04W 88/00; H04W 88/005; H04W 88/02; H04W 88/08; H04W 88/085; H04W 88/10; H04W 88/12; H04W 88/14; H04B 1/38

See application file for complete search history.

(56) **References Cited**

FIG. 1 is a front perspective view of an indoor cabinet with surface ornamentation illustrating our new design; FIG. 2 is a bottom view thereof;

U.S. PATENT DOCUMENTS

FIG. 3 is a top view thereof;

FIG. 4 is a left view thereof;

FIG. 5 is a right view thereof;

FIG. 6 is a front view thereof; and,

FIG. 7 is a rear view thereof.

The dot-dash broken lines and evenly spaced broken lines immediately adjacent to the claim, represent the bounds of the claim, while all other broken lines are directed to environment; the broken lines form no part of the claimed design.
